ATTORNEY.

UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-REGULATOR MOUNTING.

Application filed May 24, 1926. Serial No. 111,432.

The invention relates to mountings for window regulators and refers more particularly to window regulator mountings for use with sheet metal supports. The invention has for some of its objects the provision of a mounting which is simplified in construction and may be cheaply manufactured and the provision of a mounting which is so constructed that it may be readily assembled upon and secured to its support. Other objects of the invention reside in the novel features of construction and combinations and arrangements of parts as more fully herein-after set forth.

15 16 In the drawings:—

Figure 1 is an interior side elevation, partly broken away, of a vehicle door with a window regulator carried upon a mounting plate embodying my invention;

20 Figure 2 is a cross section on the line 2—2 of Figure 1;

Figure 3 is a perspective view of the mounting;

25 Figure 4 is a perspective view of a modified mounting.

My window regulator mounting is designed particularly to be secured to a sheet metal support and in the present instance is shown in conjunction with a sheet steel lock board of a vehicle door.

30 35 1 is the door having the opening 2 in its upper portion and the chamber 3 in its lower portion for receiving the window 4 when lowered from a position closing the opening. 5 is the sheet steel lock board of the door.

The window regulator for raising and lowering the window 4, as shown in the present instance, has the pivotal lifter arm 6 which is operatively connected at its outer end to the window by suitable means such as the bearing 7 secured to the arm and the channel 8 secured to the lower edge of the window. This arm has rigidly secured thereto the gear segment 9 which meshes with the pinion 10, this pinion being rotated from the crank 11 through suitable irreversible drive mechanism within the cup-shaped housing 12.

40 45 For the purpose of facilitating the mounting of the window regulator upon the lock board, this window regulator is carried as a

unit upon a single mounting which in turn is secured to the lock board. It is important that the mounting be so constructed that it may be secured to the lock board when assembled in the door. As shown, the parts of 55 the window regulator are carried as a unit upon the body 13 of the sheet metal mounting plate 14, which body is laterally spaced from the lock board. The mounting plate has at its upper end the laterally spaced legs 15 60 which extend transversely at an angle to the body 13 and terminate in the hooked tongues 16 which are adapted to embrace the lock board. These tongues extend through the elongated apertures 17 in the lock board and have the laterally offset portions 18 and 19 bearing upon the outer and inner sides, respectively, of the lock board. These laterally offset portions, before assembly of the mounting plate upon the lock board, are spaced 65 apart a distance slightly less than the thickness of the lock board so that they resiliently but firmly bear upon the opposite sides of the lock board when the mounting plate is secured thereto. To facilitate the sliding of the 70 tongues over the lock board, the extreme ends of these tongues flare outwardly as at 20. The lower end of the mounting plate has secured thereto the spacer 21 of a length to maintain the lower end of the mounting plate 75 80 spaced from the lock board at substantially the same distance as the upper end. This spacer is preferably located on the vertical median line of the mounting plate and is threadedly engaged by the screw 22 which 85 extends through the mounting plate.

To assure the firm clamping of the hooked tongues with the lock board, the spacer is so located upon the mounting plate relative to the screw for engaging the same that when 90 this screw is threaded into the spacer the mounting plate is flexed and thus placed under stress by pulling downwardly upon the same. As a consequence, play between the mounting plate and the lock board is prevented and the hooked tongues at the upper end of the mounting plate are firmly held from disengagement from the lock board. The lock board as shown is provided with the opening 95 100 23 for the passage of the housing 12 which in-

closes the irreversible drive mechanism of the window regulator and is rigidly secured to the body of the mounting plate by suitable means such as the rivets 24.

5 From the above description, it will be seen that the window regulator is carried as a unit upon a mounting and that this mounting may be cheaply manufactured in view of the fact that it and its securing means located at one end may be formed integral and by a stamping operation. By reason of the fact that the mounting may be readily secured to the lock board by first 10 passing its hooked tongues through elongated apertures in the lock board and then moving the mounting downwardly and inwardly toward the lock board and finally securing at its lower end, the mounting with the window regulator thereon may be secured 15 to the lock board when the latter is assembled in the door. Furthermore, the labor in doing so is greatly reduced. It will also be seen that by placing the mounting plate 20 under stress play and consequent rattling between this mounting plate and the lock board 25 is avoided.

The modified mounting for the window regulator, as shown in Figure 4, differs from the mounting shown in Figures 1, 2 and 3 in that the tongues 25 at the ends of the legs 26 of the resilient sheet metal mounting plate 27 are not hooked to provide portions spaced from and opposite to each other. These tongues, 30 however, have the laterally spaced portions 35 28 and 29, which are adapted to engage opposite sides of the sheet steel lock board 30 at different elevations. In securing this mounting plate to the lock board, the tongues are inserted through apertures in the lock 40 board and the mounting plate is then swung downwardly and its lower end secured in the same manner as the mounting plate previously described to place the mounting plate under stress. With this construction of mounting plate more room is required for securing the 45 same to the lock board. However, after it has been secured it functions as efficiently as the mounting plate of Figures 1, 2 and 3.

50 What I claim as my invention is:

1. The combination with a support and a window regulator, including an angularly movable member, of a mounting for said member having laterally offset portions for bearing on opposite sides of said support, and means engageable with another portion of said mounting to secure said last mentioned portion to said support and to secure said laterally offset portions from disengagement from said support.

60 2. The combination with a support and a window regulator, of a mounting for said window regulator having laterally offset portions for bearing on opposite sides of said support, and means engageable with another portion of said mounting to secure said last

65 mentioned portion to said support and to secure said laterally offset portions from disengagement from said support.

3. The combination with a support and a window regulator including an angularly movable member, of a mounting plate for said member having laterally offset portions at one end for bearing on opposite sides of said support and means engageable with the opposite end of said mounting plate for securing the last mentioned end of said mounting plate to said support and for securing said laterally offset portions from disengagement from said support.

4. The combination with a sheet metal support having an aperture and a window regulator, of a mounting plate for said window regulator having a tongue at one end extending through the aperture of said support and provided with laterally offset portions on opposite sides of said support and means for securing the opposite end of said mounting plate to said support and for securing said tongue from disengagement from said support.

5. The combination with a sheet metal support having an aperture and a window regulator, of a sheet metal mounting plate for said window regulator having a tongue at one end extending through the aperture of said support and provided with laterally offset portions on opposite sides of said support, and means for securing the opposite end of said mounting plate to said support and securing said tongue from disengagement from said support and also placing said mounting plate under stress.

6. The combination with a sheet metal support having an opening and a window regulator, of a sheet metal mounting plate for said window regulator having a hooked tongue at one end extending through the aperture in said support and adapted to embrace the latter, and means for securing the opposite end of said mounting plate to said support and for securing said hooked tongue from disengagement from said support.

7. The combination with a sheet metal support having a pair of apertures and a window regulator, of a sheet metal mounting plate for said window regulator having transverse legs at one end terminating in tongues extending through the apertures of said support and provided with portions on opposite sides of said support, means for spacing the opposite end of said mounting plate from said support and means for securing the last mentioned end of said mounting plate to said support and for securing said tongues from disengagement from said support.

8. The combination with a sheet metal support having a pair of apertures and a window regulator, of a sheet metal mounting plate for said window regulator having transverse legs at one end terminating in tongues extend-

ing through the apertures of said support and provided with portions on opposite sides of said support, a spacing block interposed between said support and mounting plate and 5 secured to the opposite end of said plate, and means for securing said last mentioned end of said mounting plate to said support and for

securing said tongues from disengagement from said support including a screw passing through an aperture in said support and 10 threadedly engaging said block.

In testimony whereof I affix my signature.

STANLEY W. NICHOLSON.
